(57) **CLAIM**

An ornamental design for a blue box, as shown and described.

DESCRIPTION

The file of this patent contains at least one drawing executed in color. Copies of this patent with color drawing(s) will be provided by the Office upon request and payment of the necessary fee.

FIG. 1 is a perspective view of an embodiment of our new design of a blue box;

FIG. 2 is a first side view of the design of FIG. 1, wherein the opposite side of the box is a mirror image of the first side view;

FIG. 3 is a second side view of the design of FIG. 1, wherein the opposite side of the box is a mirror image of the second side view;

FIG. 4 is a top view of the design of FIG. 1;

FIG. 5 is a bottom view of the design of FIG. 1;

FIG. 6 is a perspective view another embodiment of our new design of a blue box, where the blue portions are indicated using the USTPO convention of horizontal lines for blue,

FIG. 7 is a first side view of the design of FIG. 6, wherein the opposite side of the box is a mirror image of the first side view;

FIG. 8 is a second side view of the design of FIG. 6, wherein the opposite side of the box is a mirror image of the second side view;

FIG. 9 is a top view of the design of FIG. 6;

FIG. 10 is a bottom view of the design of FIG. 6;

FIG. 11 is a perspective view yet another embodiment of our new design of a blue box, where the blue portions are indicated using a checkered pattern to indicate any blue color within the range of Pantone PMS 3242-3278, PMS 2905-2995, and 7453C-7472C, specifically including Pantone 7466C;

FIG. 12 is a first side view of the design of FIG. 11, wherein the opposite side of the box is a mirror image of the first side view;

FIG. 13 is a second side view of the design of FIG. 11, wherein the opposite side of the box is a mirror image of the second side view;

FIG. 14 is a top view of the design of FIG. 11; and,

FIG. 15 is a bottom view of the design of FIG. 11.

The broken lines showing elements in the above described Figures are for illustrative purposes only and form no part of the claimed design.
